MECHANISM FOR ACTUATING THE SLAY
OF WEAVING LOOMS

Paul Breddin and Otto Wittmers, Cologne-on-the-Rhine, Germany

Application April 8, 1933, Serial No. 665,213
In Germany June 10, 1932

8 Claims. (Cl. 139—190)

The present invention relates to a mechanism for actuating the slay of weaving looms and relates to such actuating mechanisms in which the oscillatory movement of the slay is brought about by means of two pairs of cranks, arranged on the common driving shaft, and by double levers, which are pivotally attached to each of the slay swords and whose lever arms are engaged by connecting rods or links from each

10 of the cranks.

In the actuating mechanisms of this kind known heretofore, the double levers articulated to the slay swords were equal-armed and so shaped that the fulcrum is in a straight line with the two driving pins of the connecting rods. Thus the movement of the slay is such that not only at the rear limit of its stroke is there the pause in its travel, which is occasioned by this double crank drive and which is to facilitate the unimpeded passing of the shuttle through the shed, but also an equally long pause at the forward end of the stroke of the slay. Hence the time available for the travel of the shuttle is uselessly shortened and the possible maximum performance

25 of the loom reduced.

According to the present invention these drawbacks are overcome by arranging that the double lever, pivoted to each of the slay swords, is arranged as a bell-crank lever with the obtuse angle between the arms facing the crank-shaft and with the arms of different length. Hence it is possible for the forward pause in the travel of the slay to be shortened until it disappears completely, whereas the rear pause can be lengthened or the angular distance to be traversed by the crank-shaft during this pause without the slay being moved, can be determined as required.

Fig. 1 gives a side elevation showing the construction of the actuating mechanism according

40 to the invention.

Fig. 2 shows, to a smaller scale, a schematic side elevation of the actuating mechanism at the commencement of the rear rest position.

Fig. 3 illustrates the same device at the end of

45 the rear rest position.

Fig. 4 indicates the forward stroke position of the slay.

The slay 2, which is connected to the reed 1, is oscillatably carried, as usual, by the pivot 3. At the rear of each of the slay swords 4, an angular double lever 6, 7, is pivotally mounted by means of a pin 5. The ends of this double lever are hinged by means of pins 8, 9 to the links or connecting rods 10 and 11 respectively, of two cranks which are arranged on the common crank-

shaft 12, mounted at suitable height, behind the slay, in the frame of the loom (not shown). The crank 13, which acts on the upper short arm 6 of the double lever, is formed by cranking the shaft 12 itself whereas the other one, acting upon the longer lower arm 7 of the double lever, takes the form of an eccentric disc 14, secured to the crank-shaft.

If, according to the proportions shown in the drawing, the angle of the bell-crank lever open 10 towards the crankshaft amounts to about 120 degrees, the bottom arm 7, of the double lever is about three times as long as its upper arm 6, the crank-shaft being approximately on the same level as the top end of the latter, and the two 15 cranks are displaced from each other by an angle of about 130 degrees, this will produce a pause when the slay reaches the rear limit of its travel, this pause lasting whilst the crank 13, during the rotation of the crank-shaft 12 in the direction of 20 the arrow 15, traverses the angular distance of about 120 degrees between the positions shown in Figs. 2 and 3. The forward limit of stroke, shown in Fig. 4 will however be traversed by the slay without any pause, just as with any simple 25 crank drive.

During the pause in the backward stroke, which occupies a full third of the time of rotation of the crank and during which the slay finds itself in or under the widest portion of the fully 30 open shed as shown in Figs. 2 and 3, it is possible even in looms of very great weaving width, to pass the shuttle through the shed with less 35 motional resistance. Seeing that owing to this reduction in resistance, the mean speed of the shuttle may be considerably accelerated, without difficulty, this therefore admits of an appreciable increase in the speed of rotation and in the efficiency of the loom.

I claim:

1. In a device for actuating the slay carrying the shuttle race and the reed in mechanical looms, in combination with each of the two slay swords which support the slay pivotal about a horizontal axis; a bell crank lever having unequal arms pivotal about a horizontal pin, a horizontal crank-shaft carrying a pair of mutually adjacent cranks and two connecting rods which join these cranks to pins arranged at the ends of the bell-crank lever.

2. In a device for actuating the slay carrying the shuttle race and the reed in mechanical looms, in combination with each of the two slay swords which support the slay pivotal about a horizontal axis; an unequal-armed bell-crank

lever oscillating about a horizontal pin, a horizontal crank-shaft carrying a pair of mutually adjacent cranks and two connecting rods which join these cranks to pins arranged at the ends 5 of the bell-crank lever.

3. In a device for actuating the slay carrying the shuttle race and the reed in mechanical looms, in combination with each of the two slay swords which support the slay pivotal about 10 a horizontal axis; an unequal-armed bell-crank lever oscillating about a horizontal pin, a connecting rod which connects a pin of the short upper arm of the bell-crank lever to a crank of a horizontal crank-shaft and a connecting rod connecting a pin of the longer lower arm of the bell-crank lever to an eccentric disc mounted 15 on the crank-shaft adjacent to the crank.

4. Actuating means for loom slay swords comprising a shaft having a pair of cranks, a bell 20 crank lever pivoted at its angle to the slay swords and having its arms arranged at an obtuse angle with the end of one arm extending below the shaft and the end of the other arm opposite the shaft, and links connecting said arms and cranks.

5. Actuating means for loom slay swords comprising a shaft having a pair of cranks, a bell 25 crank lever pivoted at its angle to the slay swords and having its arms arranged at an obtuse angle with the end of one arm extending below the shaft and the end of the other arm opposite the shaft, said arms being inclined from

the pivot towards the shaft, and links connecting said arms and cranks.

6. Actuating means for loom slay swords comprising a shaft having a pair of cranks, a bell 5 crank lever pivoted at its angle to the slay swords and having its arms of unequal length and arranged at an obtuse angle with the end of one arm extending below the shaft and the end of the other arm opposite the shaft, and links connecting said arms and cranks.

7. Actuating means for loom slay swords comprising a shaft having a pair of cranks, a bell 10 crank lever pivoted at its angle to the slay swords and having its arms of unequal length and arranged at an obtuse angle with the end of one 15 arm extending below the shaft and the end of the other arm opposite the shaft, said arms being inclined from the pivot towards the shaft, and links connecting said arms and cranks.

8. Actuating means for loom slay swords comprising a bell crank lever pivoted at its angle to the slay swords and having its arms at an obtuse angle with one arm extending downwardly and the other arm extending upwardly, an actuating shaft with its axis of rotation located at 20 the apex of the obtuse angle formed by extended center lines of said arms, a pair of angularly disposed cranks on said shaft, and links connecting said cranks with the ends of said arms. 25

PAUL BREDDIN.
